UNITED STATES PATENT OFFICE.

JOSEF GRANZ, OF PLAUEN, GERMANY.

DEVICE FOR FORMING SHUTTLES.

1,239,177.

Specification of Letters Patent.

Patented Sept. 4, 1917.

Application filed July 3, 1915, Serial No. 38,696. Renewed January 19, 1917. Serial No. 143,418.

To all whom it may concern:

Be it known that I, JOSEF GRANZ, engineer, a subject of the German Emperor, residing at Plauen, Vogtland, in the Kingdom of Saxony and Empire of Germany, have invented certain new and useful Improvements in Devices for Forming Shuttles, of which the following is a specification.

This invention relates to shuttles and 10 means of producing the same.

The invention is clearly illustrated in the accompanying drawings, which, with the numerals of reference marked thereon, form a part of this specification, and in which—

15 Figure 1 is a vertical section of a shell for constructing a shuttle in accordance with my invention.

Fig. 2 is a side view thereof.

20 Fig. 3 is a vertical section showing the parts in position ready for the first step.

Fig. 4 is a substantially central vertical section showing the parts in the position they assume when the process is completed.

25 Fig. 5 is a view showing the parts partially removed.

Fig. 6 is a top plan of Fig. 5 with the punch holder removed.

Like letters of reference indicate like parts throughout the several views.

30 The shell shown in Figs. 1 and 2 has the general form of a well-known shuttle for embroidery machines. By the means and process soon to be described I produce a swelling in one of the sides of the shell and 35 for this purpose I employ a swage α having therein a cavity of the shape of the swell which it is desired to give to the shell. In this swage, in the cavity in the upper face thereof, is a counterplate c in the lower portion of the vertical face thereof adjacent said cavity, there being a curved recess conforming to the upper portion of the cavity. This counterplate may be secured to the swage α in any suitable manner, as by bolts d e , the

40 flanged heads of which engage upon opposite sides of the counterplate and hold it firmly in position.

i is a punch or wedge-shaped member car-

ried in a punch holder f , which latter may be forced downward in any suitable manner. The punch or wedge-shaped member i is adapted to slide vertically within a box g h and in order to limit the movement of the punch in the box there are fixed in the two sides of the box perpendicular notches m 55 with which engage pins k in the punch.

At the lower end of the box there is fixed a top swage n retained in position by the pins o in the side of the box, said pins being received in holes in the adjacent face of the 60 top swage, which latter is of the shape of the swelling to be formed in the shell x . The construction is such that the swage n cannot become separated from the box.

The operation is as follows:—The top 65 swage n is placed in the position seen in Fig. 3 and then the shell x is slipped over the front end of the parts g h and n and the punch holder f with its punch or wedge-shaped member i forced downward until the 70 shell x is forced completely into the depression in the swage α and as this is done the punch or wedge-shaped member i enters between the inner face of the part g of the box and the adjacent face of the top swage n , 75 when upon continued downward movement of the punch i the top swage n is forced laterally and this lateral movement forces the shell x into the cavity of the bottom swage and the swell b is formed upon the 80 side of the shell, thus completing the shuttle. The punch i is then raised, the top swage n moved to the left into the position shown in Fig. 5, so that the parts i g n and h may be easily taken out. Then in order to 85 remove the shuttle from the bottom swage α , the bolts d e are removed and the counter plate c is removed from its recess in the bottom swage α . Another shell is then inserted as before and the operation repeated. 90 By this means all the shuttles will be formed exactly alike which is a great desideratum.

What is claimed as new is:—

In a device of the character described, a bottom swage having a cavity of the shape 95 of the swell to be given to the shell, a coun-

ter-plate in said cavity, a vertically slidable box, a lateral pin on the lower portion thereof, a top swage laterally movable on said pin, a wedge-shaped member vertically movable in said box and independent thereof with its lower end engageable with said top swage to move it laterally when said top swage has reached the bottom of the cavity,

and means for operating said wedge-shaped member.

In testimony whereof I affix my signature in presence of two witnesses.

JOSEF GRANZ.
